UNITED STATES PATENT OFFICE.

MICHAEL H. FLYNN, OF HARTFORD, CONNECTICUT, ASSIGNOR TO THE HARTFORD VALVE MANUFACTURING COMPANY, OF HARTFORD, CONNECTICUT, A CORPORATION OF CONNECTICUT.

FLUSHOMETER.

Application filed September 25, 1922. Serial No. 590,306.

To all whom it may concern:

Be it known that I, MICHAEL H. FLYNN, a citizen of the United States, residing at Hartford, in the county of Hartford and State of Connecticut, have invented a new and useful Improvement in Flushometers, of which the following is a specification.

This invention relates to the class of valves commonly known as flushometers, 10 that is, those valves which after being opened permit the flow of a predetermined quantity of water and then automatically close.

The object of the present invention is to 15 produce a simple, cheap and relatively small valve of this character which will operate easily and surely and which can be set to allow exactly the requisite flow of water for any desired length of time.

20 In the accompanying drawings Figure 1 shows a plan of a valve which embodies the invention. Fig. 2 is a central vertical section of the same. Fig. 3 is a section of one portion of the upper edge of the valve 25 showing a bumper for a toilet seat cover which may be applied to the casing cap.

The valve has a cylindrical casing 4 with an intake opening 5 on one side, an outlet passage 6 at the lower end, a main valve 30 seat 7 intermediate the intake and outlet, and a cap 8 closing an opening at the top of the casing.

The main valve 9 which is shaped to fit and move up and down in the cylindrical 35 casing, at its lower end has a packing 10 designed to open and close the port through the main valve seat. In order to ensure the necessary close yet easily sliding fit and eliminate the possibility of sticking in the 40 casing as a result of corrosion or electrolytic action, the body of the main valve is preferably as shown, surrounded by a jacket 11 of molded noncorrosive material pressed and hardened by heat, such for instance as 45 bakelite, hard rubber or similar composition.

In the lower portion of the chamber in the main valve is a skeleton disk, spider or 50 perforated plate 12. The edges of this disk rest upon the bottom wall 13 of the chamber in the main valve, and a rigid stem 14 extends from the disk down through the opening in the bottom of the valve into the outlet passage. The opening in the bottom of the main valve is sufficiently large to 55 permit this disk and stem to perform the

function of a bell-crank lever, that is, the construction is such that no matter how rotatively the disk is dropped into the chamber of the main valve, when the lower end of the stem is pushed sidewise the disk fulcrums on its edge on one side and the edge on the diametrically opposite side lifts. This tilting disk and its stem, or universal bellcrank lever, is carried up and down with the main valve as the outlet port is opened and closed. The upper end of the main valve has a tubular opening 15 and adapted to open and close this passage is an auxiliary or control valve 16. The control valve has a spider stem 17 that does not close the 70 passage but is guided up and down by the wall thereof. At the lower end of this stem is a head 18 and thrusting between this head and upper end wall of the main valve, is a spring 19 that tends to keep the auxiliary valve on its seat. The head at the lower end of the auxiliary valve stem extends just above the tilting disk or universal bellcrank lever and when the disk is rocked by pushing its stem sidewise the head will be engaged and lifted so as to open the auxiliary 75 valve from its seat.

Through the main valve is a passage 20 that provides communication from the intake opening to the space in the casing above 80 the main valve. The effective area of this passage, or by-pass, is controlled by a tapering valve 21 that has a threaded stem 22 screwed into the upper end of the passage.

In an opening in one side near the lower 90 end of the casing is a thimble 23. This thimble is held in place by a cap 24 that is screwed into the opening. A pin 25 is arranged to reciprocate in an opening through the thimble and impinge against the stem 95 of the bell-crank lever. A packing 26 and nut 27 are provided for preventing leakage around this pin. The outer end of the pin has a head 28 and loosely mounted on the pin inside of the head is a washer 29. The handle 30 extends through the cap and on the inside has a flange 31 that is larger than the opening through the cap. A spring 32 arranged between the thimble and the washer presses the washer outward against the flange on the inner end of the handle and thus yieldingly holds the handle in position. The inner end of the handle is shown as concaved and in the cavity is a 100 seat 33 that is designed to impinge against 105 the flange on the outer end of the handle. The handle 30 is provided with a handle 110

the head of the pin when the handle is thrown out of line in any direction.

When the handle is tipped the teat pushes the pin inward and this swings the bell-crank and causes it to lift the control valve and relieve the water pressure above the main valve, which pressure is the same as the pressure in the intake. After this pressure is relieved the main valve is forced upward by the intake pressure. As the handle is released its spring causes it to resume normal position and the pin allows the rocker lever to resume its normal position and the control valve to be closed by its spring. With the control valve closed the pressure above the main valve builds up as fast as the water flows through the by-pass in the main valve and when the pressure above the valve equals the intake pressure the main valve closes the outlet port. The time interval during which the pressure will build up above the main valve depends upon the adjustment of the needle valve that controls the by-pass through the main valve. Thus by adjusting the needle valve the time of the closing of the main valve and the amount of flow of water through the casing may be exactly regulated. As a result of the employment of a non-corrosive composition jacket about the main valve, that valve can be closely fitted within the casing and yet it will not stick as a result of corrosion or other deleterious action of water on the parts in the casing. The handle is held in place by its spring and not by the pin which rocks the bell-crank, and the teat on the inner end of the handle impinges against the center of the head of the pin whenever the handle is turned, so that the pin is pushed in on substantially the line of its axis. This eliminates the possibility of excess friction between the pin and the wall of the opening in the thimble which guides the pin.

In order to provide a bumper for preventing a toilet seat cover when thrown open from banging this valve a clamp 34 may be formed with flanges 35 shaped to receive and clasp a cushion 36, and flanges 37 that may be sprung upon the edges of the casing cap.

After the clamp has been located on the cap

in the desired position a screw 38 is turned in from the under side so as to cause the flanges to grip the edge of the cap.

The invention claimed is:

1. A flushometer comprising a casing with an intake, an outlet and a valve seat intermediate the intake and outlet, a main valve with a passage through it fitted to and movable in the casing on the intake side toward and from the valve seat, an auxiliary valve carried by and adapted to be positively reciprocated for opening and closing the passage through the main valve, a stem fixed to the auxiliary valve and extending downward into the passage through the main valve, a universal rocker lever carried by the main valve and adapted when tilted to engage the lower end of the auxiliary valve stem and raise the auxiliary valve from its seat, a spring carried by the main valve and engaging the auxiliary valve stem and normally closing the auxiliary valve, and means for rocking said lever.

2. A flushometer comprising a casing with an intake, an outlet and a valve seat intermediate the intake and outlet, a main valve with a passage through it fitted to and movable in the casing on the intake side toward and from the valve seat, an auxiliary valve carried by and adapted to be positively reciprocated for opening and closing the passage through the main valve, a stem with an enlarged head fixed to the auxiliary valve and extending downward into the passage through the main valve, a spring carried by the main valve and engaging the enlarged head of the auxiliary valve stem for closing the auxiliary valve, a disk loosely mounted in the main valve opening below and normally out of engagement with the enlarged head of the stem of the auxiliary valve and adapted when tilted to engage said head for opening the auxiliary valve, a stem projecting from said disk into the outlet port, and means for swinging said stem sidewise and causing the disk to tip and engage the head of the stem and open the auxiliary valve against the pressure of said spring.

MICHAEL H. FLYNN.
